UNITED STATES PATENT OFFICE.

WILLIAM KENNEDY AND ERNST T. KREBS, OF CARSON CITY, NEVADA.

FUEL-BRIQUET.

1,273,619.

Specification of Letters Patent. Patented July 23, 1918.

No Drawing.

Application filed February 13, 1918. Serial No. 216,995.

To all whom it may concern:

Be it known that we, WILLIAM KENNEDY and ERNST T. KREBS, both citizens of the United States of America, and both residing at Carson City, in the county of Ormsby and State of Nevada, have invented certain new and useful Improvements in Fuel-Briquets, of which the following is a specification.

Our invention relates to improvements in fuel briquets, and it consists in the composition containing the ingredients or materials hereinafter set forth.

In certain parts of the United States there are large deposits of oil shale. Attempts to make use of these oil shales as a fuel have been made, but failure has always resulted because of the fact that they have not proved commercially practical. The principal reason for failure to make successful use of oil shales as a fuel lies in the fact that when pieces of the shale are burned in the manner and under the conditions in which coal is burned, the shale instead of being reduced to an ash, remains in its original shape and size. This prevents the consumption or the combustion of the carbonaceous matter contained in the shale.

Furthermore, the lumps of shale, since they cannot be reduced to ash, cannot be used in an ordinary furnace because of that very fact. Instead, therefore, of giving up its carbon content to produce heat, as is done with ordinary coal, and thereafter disintegrating so as to be readily removed from the furnace, as, for instance, by rocking the grate bars, the shale remains in the same form in which it was introduced in the furnace and soon tends to clog up the latter, unless it is removed bodily.

Now we have discovered that by reducing an oil shale to a coarse powder and then binding this powder together with a liquid or semi-liquid binder a briquet can be made which will permit a greater combustion of the carbon content of the briquet and, at the same time, will disintegrate so that it may be readily removed from the furnace.

A further object of our invention is to provide a briquet of the type described whose fuel value is greatly increased over the combined fuel value of the original component parts, that is to say of oil shale and binder, due to better combustion.

As is well known, crushed or fine shale, unlike coal, has no adhesive or cohesive properties in its natural state when ignited;

therefore, the mass when burning chokes itself by shutting out the circulation of air through the burning mass and results in very imperfect combustion of the fuel content of the shale. Burning oil shale *en masse* does not consume all the so-called "shale coke" besides there is a large amount of carbon left in the shale due to imperfect combustion of the heavy oils because of non-oxidation due to the density or non-porous character of the shale. This unconsumed carbon amounts to a considerable portion of the fuel value of the shale, depending upon the amount of so-called "shale coke" and heavy oils in the shale increasing as these are greater and decreasing as these are less and the light oils greater. Besides oil shale when burned *en masse* retains its original shape and bulk losing only in weight; in other words, it does not disintegrate after being burned, except where a previous fracture existed it might separate. A fire box filled with oil shale in its original state after being burned would still be filled with the burned undisintegrated shale, and shale thus burned does not give its full fuel value. When it is crushed to a coarse powder and mixed with a hydrocarbon binder such as a heavy fuel oil preferably in which has been dissolved a resinous material like rosin or other hydrocarbon like asphaltum and mixed while hot and compressed into briquets, it makes a superior fuel in heat units to that which is produced by lump shale and binder when burned separately. When such a briquet is burned it gradually disintegrates as the shale particles become ignited through the agency of the binder, and when this process of disintegration takes place each particle of shale being ignited the briquet falls disintegrated into a burning mass having the power to more or less completely consume its inherent carbon, and in proportion as the carbon is consumed is the fuel value of the shale increased, and in that proportion do the shale particles become soft and ashy.

The fineness to which the shale should be crushed depends upon the character of the shale, the tight and hard shales being crushed to a finer and the soft and loose shales to a coarser mesh.

In carrying out our process, we take the oil shale and reduce it to a more or less coarse powder by any suitable crushing device. We prefer to use a liquid or semi-liquid fuel as a binder, thus aiding more or

less complete combustion of all fixed carbon and shale coke therein when burned. For this binder we prefer to use a heavy crude oil, the best for the purpose being of an asphaltum base or even asphaltum itself which is liquid or semi-liquid at different temperatures in which has been dissolved, whichever binder is used, a small quantity of resinous material, such as rosin, which is mixed with the crushed shale in a heated condition. The proportions of the binder would vary in accordance with the particular binder used, but as an instance of an efficient mixture, we may take one ton of shale, when reduced to coarse powder, and with it mix from five to fifteen gallons of crude oil such as that set forth above.

The plastic mixture which results from the mixture of the binder and the shale is then run through a briquetting machine under great pressure. Any suitable briquetting machine may be used but we prefer to use a machine of the hydraulic type which forms briquets that readily hold their shape in transportation and in use with any fuel consuming device.

While we have mentioned crude oil as being an efficient binder, any liquid or semi-liquid which will hold the shale dust together in the form of a briquet may be used. We have found that water may be used effectively, although of course a binder containing hydrocarbon has the double function of cementing the particles of shale dust into the briquets and of adding to the fuel value of the briquets.

A briquet such as that set forth in the present application has a large part of its carbon content consumed. Furthermore, it disintegrates so that it may be readily removed from the furnace in the ordinary manner. The result is that large deposits of oil shale are thus rendered available for use as fuel, which could not be used under ordinary circumstances.

We are aware that fuel briquets, broadly speaking, are old but the ordinary fuel briquet is made for the purpose of utilizing granular material, such as coal dust, coal slack, sawdust, and other material of a like nature. On the other hand, the briquet which forms the subject of the present invention is designed to make available, for fuel consumption, oil shales which heretofore have been practically worthless as fuel. The oil shales when burned in their natural state retain a portion of their carbon content unconsumed and, as stated above, they do not disintegrate. By forming a briquet of crushed shale a greater combustion of the carbon content is assured and the dis-

integration of the briquet permits it to be used in the ordinary way.

By our process we claim to make use of a hitherto useless fuel and create a useful one by using the briquetting process with a special binder to bind a raw material entirely new to the briquetting industry which is first reduced to a coarse powder to develop its full fuel value when again bound into a mass in the form of a briquet, thus producing an entirely new and different product which, when burned, will develop more heat units than its component parts will develop when these same component parts are burned separately. In this way we produce a fuel far cheaper in the Western States of the United States than any other.

It must be understood that the oil shale can be bound with good results without using a resinous material, and it is our intention to use the binder with or without such resinous material if, for any reason, this resinous material is not easily obtained or its price prohibitive. It is, however, desirable to use this resinous material to obtain the best results.

It must also be understood that if other materials, such as coal slack, coal or coke dust, peat or sawdust can be had at a small cost, we intend to incorporate them with the crushed oil shale and compress them into briquets which will make very desirable fuel.

We claim:—

1. A fuel briquet comprising a body portion of comminuted oil shale, and a binder for holding the shale together.
2. A fuel briquet comprising a body portion consisting of oil shale in the form of a coarse powder, the particles of the shale being held together with a liquid or semi-liquid binder.
3. A fuel briquet consisting of a body portion of oil shale in powdered form held together by a binder containing carbonaceous matter.
4. A fuel briquet which consists of a body portion of coarsely powdered oil shale rock and a liquid or semi-liquid binder containing combustible hydrocarbons.
5. A fuel briquet which consists of a body portion of crushed oil shale and a heavy semi-liquid binder of carbonaceous matter in which has been dissolved a resinous material.

WILLIAM KENNETT.
ERNST T. KREBS.
